UNITED STATES PATENT OFFICE.

LIPA POLINKOWSKY, OF BRUSSELS, BELGIUM, ASSIGNOR TO WESTERN ELECTRIC COMPANY, OF NEW YORK, N. Y., A CORPORATION OF ILLINOIS.

TELEPHONE-EXCHANGE SYSTEM.

1,161,411.

Specification of Letters Patent. Patented Nov. 23, 1915.

Application filed August 17, 1914. Serial No. 857,130.

To all whom it may concern:

Be it known that I, LIPA POLINKOWSKY, a subject of the Russian Emperor, residing at 19 Rue Brialmont, Brussels, Belgium, have 5 invented certain new and useful Improvements in Telephone-Exchange Systems, of which the following is a full, clear, concise, and exact description.

This invention relates in general to telephone exchange systems in which automatic switches are utilized to establish the desired connection between a calling and a called line, and relates more particularly to the control of certain of such switches of the 15 general type, which operate to select or seize certain electrically distinguished circuits from a plurality of equivalent circuits or equipments not so distinguished. Switches of this general type are employed in automatic systems for the purpose of selecting 20 and seizing an idle connecting or trunk line from a plurality of such trunks, for selecting and seizing a calling line from a plurality of such lines, or in general whenever 25 it is desired to select and seize a particular circuit or equipment from a plurality of such circuits or equipments.

More specifically the invention relates to a test circuit or system for switches of the 30 type referred to above. It is usual in connection with such switches to provide a test circuit which includes a device such as a test relay which is responsive to an electrical condition individual to the terminals of the 35 lines which it is desired to seize, and to provide devices set in operation by the response of such test relay to cause the stopping of the switch and the opening of the test circuit, the opening of the test circuit rendering 40 the switch ineffective for seizing other lines. It is also usual to arrange the circuits and apparatus so that the switch will again start in motion if the test relay does not remain energized a substantial time, but 45 ordinarily no provision is made to prevent the opening of the test circuit in such event, so that the switch may be again started in motion, but will be, due to the opening of the test circuit, thereafter ineffective to seize a 50 line.

It is therefore an object of the present invention to not only prevent the stopping of the switch by a momentary energization of the test relay, but to also provide means for 55 preventing the switch from being thereaf-

ter rendered ineffective for seizing other lines. With this object in view, and in accordance with this invention, circuits and apparatus are provided for introducing a definite and substantial time interval between the initiation of the operation of the test relay and the opening of the test circuit, so that a momentary energization of the test relay will not alter the test circuit, and the test relay may thereafter operate 60 to cause the switch to seize a line.

In systems employing switches of the type under consideration, a momentary energization of the test relay may occur from various causes other than the contacting of the 70 switch with an electrically distinguished line,—for instance, causes such as grounds, crosses or short circuits; but the most frequent cause is due to two or more switches attempting to simultaneously connect to the 75 same electrically distinguished line. In case this should occur in a system employing the test circuit of this invention, not only will more than one switch be prevented from seizing and holding the line, but the switches 80 which fail to hold the line will not thereafter be rendered ineffective to seize other electrically distinguished lines and the calls associated with said switches will not be lost.

In the specific embodiment of the invention, which is hereinafter disclosed, there is associated with each switch, in addition to a test relay, a power control relay and a sequence switch. The circuits are so arranged that the operation of the test relay will cause the operation of the power control relay, which will in turn open the circuit of the motor magnet of the switch to stop the switch, and also to establish a circuit 90 for the sequence switch to drive the same through two or more adjacent positions. The sequence switch contacts are so arranged that the test circuit will not be opened by the sequence switch until after 95 the sequence switch has moved through two or more adjacent positions, and as the circuit for the sequence switch will be maintained only as long as the test relay remains energized, it follows that if the test relay 100 fails to remain energized long enough for the sequence switch to move through at least two positions, the test circuit will not be opened. By virtue of this arrangement, a momentary energization of the test relay 105

can do no more than drive the sequence switch through one position, and hence the test circuit will not be opened by such a momentary energization, and the switch will not be rendered ineffective for thereafter seizing other lines.

The invention is diagrammatically shown in the drawing as employed in connection with a plurality of selector switches, sufficient of two selector switches being shown to illustrate the invention, all parts not directly concerned in the invention being omitted for the sake of clearness.

Referring to the drawings, two selector switches are shown diagrammatically at 1 and 2. As both of these switches are identical in construction, a description of one will suffice for both. On selector switch 1 there is shown a brush carriage carrying brushes 3, 4 and 5, which are adapted to sweep over, make contact with and test the rows of terminals of the group of lines in which an idle line is located. The terminals of only two such lines are diagrammatically shown in the drawing, such rows being indicated at 6 and 7, it being understood, however, that in such switches as actually constructed, as many rows of terminals are provided in the switch as there are lines which it is desired to reach. Also associated with the brush carriage is a brush 8 which in its normal position makes contact with the normal contact 9, but which is adapted when the carriage is being moved to make and break contact with the interrupter plate 10 to ground, such brush making contact with the interrupter plate at all times, except when the brushes 3, 4 and 5 are exactly centered upon a row of terminals.

The brush carriage is driven from the constantly rotating power shaft 11 through the agency of two friction disks 12 and 13, the friction disks being coupled together by means of the power magnet 14 when such magnet is energized. A holding magnet 15 is also provided which acts, when energized, as a magnetic brake to stop the rotation of the brush carriage.

Associated with the selector switch 1 and individual thereto is a sequence or steering switch 16. The construction of sequence or steering switches of the type indicated is well known in this art and need not be herein further described. The purpose of the sequence switch 16 is, in its successive positions, to establish the various circuits by means of which the setting and restoration of the selector switch 1 may be controlled.

The sequence switch 16 is indicated as being capable of stopping only in its first or normal position and in the 7th, 8th and 18th positions, for the reason that it is only necessary for the understanding of this invention that the sequence switch should stop in such positions; however, it is obvious that be-

tween its 1st and 7th positions the sequence switch may stop as desired to control the selection of the necessary group of lines in which the idle line is to be selected in any wellknown manner, and also that between its 7th and 18th positions it may stop to control the establishment of the through or talking connection, to initiate the restoration of some other switch, or to bring about other circuit changes.

The selector 2 is provided with brushes 17, 18 and 19 which are adapted to travel over rows of contacts, two of such rows being indicated at 20 and 21. The interrupter brush is indicated at 22, the interrupter plate 80 at 23, and the normal contact at 24. The power magnet of the selector 2 is indicated at 25 and the holding magnet at 26. The sequence switch which is individual to selector 2 is indicated at 27.

Individual to the selector 1 is the test relay 28, which is provided with two windings, and the power control relay 29. A similar test relay 30, and power control relay 31 is associated with the selector 2. Connected with the row of terminals 6 in selector 1 and the row of terminals 20 in selector 2 are three conductors, comprising a line 32, and connected to the row of terminals 7 of selector 1 and row 21 of selector 2 are three conductors comprising line 33. A relay 34 individual to the line 32 is shown connected in the test conductor of such line and a relay 35 individual to the line 33 is shown connected in the test conductor of 100 such line.

The invention, however, will be better understood from the description of the operation thereof which follows: Assume that the sequence switches 16 and 27 have been 105 started from their normal position, and having performed their intermediate functions, come to rest in position 7, which is the hunting or test position. Assume also that two calling subscribers have appropriated the 110 lines 36 and 37 and that the connection desired by such subscribers includes an idle line. In response to circuit changes established by such calling subscribers the power magnets 14 and 25 are energized over sequence switch springs 160 and 270 to start the brush carriages of selectors 1 and 2 in motion, to hunt for an idle line. Assuming that both the lines 32 and 33 are idle, a characteristic potential will be placed on the 120 terminals 6, 7, 20 and 21, such terminals being connected to battery through the relays 34 and 35. If selector 1, for instance, reaches the row of terminals 6 before selector 2 reaches the row of terminals 20, 125 which are associated with same line, namely line 32, the relay 28 will be energized over a circuit which may be traced from battery through the relay 34, terminal 6, brush 5, sequence switch spring 161, left-hand wind- 130

ing of the test relay 28, sequence switch spring 162 to ground, provided the sequence switch 16 is in either of positions 7 or 8. The test relay 28 will close its front contact 5 and establish a circuit, which will include the right-hand low resistance winding of the test relay, and the winding of the power control relay 29 to ground. A branch of the circuit last traced includes the sequence 10 switch spring 163, interrupter brush 8 and interrupter plate 10 to ground, which branch circuit will shunt the relay 29 and prevent it from operating until such shunt circuit is opened by the brush 8 falling in between 15 two teeth on the interrupter plate 10 which will occur when the brushes 3, 4 and 5 are accurately centered on the row of terminals 6. The relay 29 will then operate and open the circuit for the power magnet 14 and also 20 close at its front contact a circuit for the holding magnet 15, including sequence switch spring 164, thus causing the energization of the holding magnet and the stopping of the brush carriage on the row of 25 terminals 6. The relay 29 will also close at its front contact a circuit through the power magnet of the sequence switch 16, and will drive the sequence switch from position 7 to 8, and if the test relay remains 30 energized a sufficient time, the relay 29 will hold up long enough to drive the sequence switch through position 8. It will be observed that in both positions 7 and 8 of the sequence switch 16, the test relay 28 will be 35 associated with the test circuit of the selector and will be in position to respond when such selector makes contact with the terminals of an idle line, and that a momentary energization of the test relay will 40 not drive the sequence switch through both positions 7 and 8.

It may easily happen that the selectors 1 and 2 may be simultaneously hunting for an idle line in a group of lines appearing in 45 both of such selectors and therefore that the movable brushes of both selectors may simultaneously reach terminals associated with the same line, for instance, the brushes 3, 4 and 5 may make contact with the row 50 of terminals 6 at the same time that brushes 17, 18 and 19 make contact with row of terminals 20, the row of terminals 6 as well as the row 20 both being connected to line 55 32, in which case the test relay 28 may be energized over the circuit previously traced and the test relay 30 may be energized over a circuit including the relay 34, a test conductor of the line 32, terminal 20, brush 19, sequence switch spring 271, left-hand high 60 resistance winding of the test relay 30, sequence switch spring 272 to ground. The relay 30 closes a circuit for itself including its right hand low resistance winding and power control relay 31 to ground. When the shunt around the relay 31 is removed when the brushes are accurately centered on the terminals 21 by the opening of the interrupter 65 circuit, the relay 31 will operate deenergized.

tential of the battery associated with the test conductor of line 32 will be insufficient to maintain both of the said relays energized, so that one of said relays will fall back, or in exceptional cases both of said 70 relays may fall back. However, it may easily happen that both of said relays may have been energized long enough to close their front contacts and operate their respective power control relays 29 and 31, in 75 which case the sequence switches 16 and 27 would be driven out of position 7 to position 8 and the motor magnets of the selectors 1 and 2 would be deenergized. In the case of the relay 28 which we will assume held up, 80 this would be the normal operation and the circuit of the power control relay 29 would be maintained long enough to drive the sequence switch not only from position 7 to position 8, but also through position 8. The 85 brush carriage of selector 1 would therefore stop with the brushes 3, 4 and 5 centered on the terminals 6.

In the case of relay 30 which we will assume has fallen back, the momentary 90 energization thereof in addition to momentarily energizing the power control relay 31 and driving sequence switch 27 to position 8 also opened the circuit of the motor magnet 25. The motion of the brush carriage of the 95 selector 2 may have actually been stopped but when relay 30 falls back relay 31 also falls back, and the brush carriage selector 2 will again start in its hunting movement. However, the test relay 30 was not energized long enough to cause the sequence 100 switch 27 to move out of position 8, so that the test circuit of the selector 2 is still maintained and the selector may still seize an idle line. It is obvious, therefore, that had the 105 test circuit been closed only in the seventh position of the sequence switch 7 instead of in both the seventh and eighth positions, the selector 2 would have returned to normal 110 without being able to seize another idle line and the call associated with such selector would have been lost. The selector 2 having again been started in motion as above described with the sequence switch 27 in position 8, and having reached the row of 115 terminals 21 associated with idle line 33, the test relay 30 will again operate, and in this case remain energized over a circuit which may be traced as follows: battery, relay 35, line 33, terminal 21, brush 19, sequence switch spring 271, left hand high resistance winding of relay 30, sequence switch spring 272 to ground. The relay 30 closes a circuit for itself including its right hand low resistance winding and power control relay 31 to ground. When the shunt around the relay 31 is removed when the brushes are accurately centered on the terminals 21 by the opening of the interrupter 120 circuit, the relay 31 will operate deenergized.

ing the magnet 25, energizing the holding magnet 26 and driving the sequence switch 27 out of position 8. The brush carriage of selector 2 will therefore stop and connection 5 to the idle line will have been made. Both selectors will therefore have seized idle lines and neither call would have been lost.

In case both of relays 28 and 30 should fall back, both selectors 1 and 2 would be 10 again started and with their sequence switches in position 8 and unless they should both again attempt to simultaneously seize the same line which is extremely unlikely, neither call would be lost. Still another 15 condition under which the test relay associated with a selector switch, of the type herein disclosed, may become momentarily energized without the switch seizing a line may be brought about by the failure of the 20 holding magnet to bring the brush carriage to a stop before the brushes have overrun the terminals—in other words, the momentum of the brush carriage may be sufficient to carry the brushes beyond a row of terminals before the motion of the brush carriage 25 is stopped. In this case, assuming that the brushes have contacted with the terminals of an idle line, and have not been stopped until after they have traveled beyond such 30 row of terminals, the line and power control relays will have been momentarily energized, in which case the sequence switch will have moved only from position 7 to position 8, because as soon as the brushes leave the 35 row of terminals the line and power control relays will become deenergized. The momentary energization of the test relay therefore would not render the switch ineffective for seizing other lines for the reason that as 40 soon as a line relay is deenergized the switch will again start on its hunting movement with the test circuit closed in the eighth position of the sequence switch.

It is obvious that because two test 45 positions are provided on the sequence switch a momentary energization of the test relay from any cause will not disable the selector from thereafter selecting an idle line. The function therefore of the double test position 50 of the sequence switch may be stated to be the provision of a time interval between the initiation of the operation of the test relay and the opening of the test circuit at the sequence switch, whereby the test circuit is 55 not altered by a momentary energization of the test relay.

I claim:

1. In a telephone exchange system, the 60 combination with a selector, of a driving circuit and a test circuit therefor, a test relay in said test circuit, means controlled by the response of said relay to open said driving circuit and to disable the test relay for further testing, and means for interposing a 65 time interval between the opening of the

driving circuit and the disabling of the test relay.

2. In a telephone exchange system, the combination with a selector, of a driving circuit and a test circuit therefor, a relay in 70 said test circuit and means controlled by said relay when actuated to open the driving circuit, and means operated only in case said relay remains actuated a predetermined interval to disable the selector for further test- 75

3. In a telephone exchange system, the combination with a selector, of a driving circuit therefor, a test circuit, a relay controlled thereby which when actuated opens 80 the driving circuit, and means operated only in case said relay remains actuated a predetermined interval to open the test circuit.

4. In a telephone exchange system, the combination with a selector, of a sequence 85 switch associated therewith, a test circuit for said selector maintained closed by said sequence switch in a plurality of successive positions, and a circuit for advancing said sequence switch maintained closed as 90 long as said test circuit is closed, whereby said test circuit is opened by said sequence switch only in case such test circuit remains closed sufficiently long for the sequence switch to move through the positions individual to the test circuit.

5. In a telephone exchange system, the combination with a selector, of a sequence switch associated therewith, a test circuit and a driving circuit controlled by said 100 sequence switch, and a relay controlled by said test circuit and cooperating in the control of said driving circuit and adapted only in case it remains actuated a predetermined interval to cause said sequence switch to 105 open said test circuit.

6. In a telephone exchange system, the combination with a selector, of a sequence switch associated therewith, a driving circuit for the selector, a test circuit closed in 110 two successive positions of said sequence switch, a test relay therein, and a relay controlled by said test relay and which when actuated upon the energization of said test relay when the selector connects with an idle line is adapted to open the driving circuit and only when maintained energized a pre- 115 determined interval, to advance the sequence switch through both positions individual to the test circuit.

7. In a telephone exchange system, the combination with a selector, of a sequence switch associated therewith, a driving circuit and a test circuit for the selector, said test circuit being closed through a plurality 125 of successive positions of said sequence switch, and a test relay in said test circuit adapted upon its response to move said sequence switch through a plurality of positions individual to the test circuit and if re- 130

stored prematurely to hold the sequence switch in one of the succeeding test positions and to reclose the driving circuit of the selector for further testing movement.

5. 8. In a telephone exchange system, the combination with a selector, of a sequence switch associated therewith, a driving circuit and a test circuit for the selector, said test circuit being closed through a plurality of successive positions of said sequence switch, and a test relay in said test circuit adapted when energized to move said sequence switch through a plurality of positions individual to the test circuit and if restored prematurely to hold the sequence switch in one of the succeeding test positions and to reclose on its back contact the driving circuit of the selector for further testing.
15. 9. In a telephone exchange system, the

combination with a plurality of automatically operating switches, a plurality of lines multiplied thereto, a driving circuit and a test circuit for each such switch, and a relay controlled thereby adapted when actuated upon connecting with an electrically distinguished line to open the driving circuit and, if maintained actuated sufficiently long, to render ineffective the test circuit, the potential on such line being insufficient to maintain more than one relay excited sufficiently long to render its testing circuit ineffective.

In witness whereof, I hereunto subscribe my name this 28th day of July A. D., 1914.

LIPA POLINKOWSKY.
